UNITED STATES PATENT OFFICE.

JOHN C. McLAUGHLIN, OF JERSEY CITY, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE

No. 900,574.

Specification of Letters Patent. Patented Oct. 6, 1908.

Application filed July 7, 1908. Serial No. 442,367.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to the platen-shifting mechanisms of the carriages of type-writing machines.

It is the practice to make the platen frames as light as possible, to avoid weighting the carriage, which must move very promptly between type impressions. It is also the practice to counterbalance the platen frame by means of a spring, so as to make the platen-shift-key easier to operate. For these reasons it is sometimes found that in rapid operation the platen frame is liable to quiver or shake up and down upon the carriage, these movements being very slight, but still objectionable because they are in up and down direction, and hence tend to cause irregularity in the line of writing, since the types strike upon the front of the platen, and slight variations in the position of the platen cause a corresponding unevenness in the line of writing.

The object of my invention is to overcome this difficulty; and to this end, I arrange latches to operate between the platen frame ends and the ends of the carriage, upon which the platen frame is mounted, which latches hold the platen frame rigidly to the carriage. I also provide the usual shift-key with means to release the latches in advance of shifting the platen for writing capital letters. Upon the return of the platen frame to normal position, the latches snap again into normal positions to hold the platen frame to the carriage.

The latches are preferably fixed at the ends of the carriage upon a single rock shaft, to catch over a rod or other device which is fixed upon the platen frame; and upon the usual shift rail I provide an auxiliary plate or rail which is constructed to engage a device that projects from said latch shaft. This projecting device is preferably in the form of an anti-friction roll swiveled upon a collar that is fixed to said latch shaft. The auxiliary plate or rail engages said swiveled roll to release the latches, and then the main shift-rail performs its usual func-

tion of shifting the platen frame up for writing capital letters. The auxiliary plate or rail is sufficiently broad to remain in constant engagement with said latch roll during the shifting operation, so as to hold the latches released until the platen drops to normal position.

In the accompanying drawings, Figure 1 is a sectional side elevation of the platen frame and carriage, and a part of the shifting mechanism of the well known Underwood typewriting machine; the parts being shown in normal positions, the platen frame resting upon the carriage, and locked thereto by the latches. Fig. 2 is a skeleton view corresponding to Fig. 1, but showing the initial movement of the shifting mechanism, whereby the latches are swung forward to release the platen frame for its upward movement. Fig. 3 is a view similar to Fig. 2, but showing the platen elevated to receive the impressions of capital types. Fig. 4 is a front view of the machine with the parts shown in the Fig. 1 position.

Type bars 1, having lower case types 2 and upper case types 3, strike upon the front side of a cylindrical platen 4, which is journaled by an axle 5 in the ends 6 of a platen frame, which also comprises a paper-shelf 7. The platen frame is mounted upon a carriage 8, which runs upon front and rear rails 9, 10. The platen frame is hung upon a swinging bail, comprising a pair of arms 11 fixed to and projecting forwardly from a rock-shaft 12 journaled upon carriage arms 13, whereby the platen frame is guided in its upward and downward movements in the usual manner; a spring 14 being coiled about said shaft to counterbalance the weight of the platen frame. The platen frame is shifted up by means of a key 15 mounted upon the front end of an elbow lever 16, an upstanding arm 17 of which bears upon the rear edge of a plate-like arm 18, forming part of a frame swinging about a rock-shaft 19, journaled in the framework 20 of the machine. Said swinging frame also comprises a rail 21 which serves as a shift rail for the platen-frame, the latter having a roll 22 to be engaged by said rail to elevate the platen frame. The construction so far described is in common use in said Underwood machine.

A rigid connection between the platen frame and the carriage is made by means

of two latches 23. These are fixed at their lower ends upon the ends of a rock-shaft 24, which is journaled in a pair of brackets 25 fixed to and depending from the ends of the carriage 8. A spring or springs 26 coiled about the rock shaft 24 tend constantly to press said latches rearwardly to catch over a rod 27, usually fixed in and forming part of the platen frame; these latches being fitted 10 to hold the platen frame firmly to the carriage, whereby up and down vibration of the platen in rapid operation is prevented, since the carriage is not only sufficiently heavy to hold it firmly down upon its tracks, but is 15 also tightly fitted to the rail 10, by means of collars 28 encircling the under side of the rail.

Upon depression of shift-key 15, the arms 16, 17 swing about a fulcrum 29, the 20 arm 17 pressing forwardly the plate or frame 18 about the axis 19, thereby lifting the rail 21. Said rail is normally a trifle below the roll 22 on the platen frame, so that the initial upward movement of said 25 rail is idle so far as said roll is concerned. I provide upon said rail, however, an auxiliary rail or plate 30, to engage a roll 31, which is swiveled upon a collar 32 fixed upon the rock shaft 24, so that such idle upward movement of the rail 21 enables the auxiliary rail 30 to turn said shaft 24 and swing the latches forwardly to the Fig. 2 30 position, thereby releasing the platen frame, so that the continued upward movement of 35 the rail 21 may have the effect of lifting the roll 22, together with the platen frame, to the capital printing position, shown at Fig. 3. During this movement, the roll remains in engagement with the front face of the auxiliary rail or plate 30, the latter having sufficient breadth (or height) to maintain engagement of such roll during the entire 40 shifting operation. The roll 31 is provided about midway of the length of the platen 45 frame or of the rock-shaft 24, and constitutes a projection or lug for engagement by the shift-rail 30 for the purpose specified. A rolling projection is preferred to a fixed 50 projection, since it avoids friction against the auxiliary rail 30 during the writing of capital letters, due to the traveling of the carriage 8, although the invention is not limited to the rolling projection. Upon relieving the key 15 from pressure, the platen 55 frame settles down to its bearings on the carriage 8, the frame 18 and the key lever 16, 17 resuming normal positions, and the springs 26 throwing the latches 23 rearwardly to reconnect the ends of the platen 60 frame to the ends of the carriage.

Thus it will be seen that by means of a very simple and inexpensive change in existing machines, the difficulties above noted may be avoided.

65 Variations may be resorted to within the

scope of the invention, and portions of the improvements, may be used without others.

Having thus described my invention, I claim:

1. In a typewriting machine, the combination with a carriage, a platen, and a platen frame mounted on the carriage to shift for writing capitals, of latches at the ends of the carriage to catch over the platen frame to hold it in one position, a rock-shaft extending along and mounted upon the carriage, both of said latches being fixed to said rock-shaft, and a key-operated mechanism to shift the platen frame, a rail being operated by said key to engage a part projecting from said rock-shaft to rotate it to release the latches, to permit the platen frame to be shifted by said key-operated mechanism. 70

2. In a typewriting machine, the combination with a carriage, a platen and a platen frame mounted on the carriage to shift for writing capitals, of latches at the ends of the carriage to catch over the platen frame to hold it in one position, a rock-shaft extending along and mounted upon the carriage, 85 both of said latches being fixed to said rock-shaft, a roll swiveled on said rock-shaft about midway of the length of the latter, a shift-key operating a rail to engage said roll to rock the shaft and release the latches, 90 and a platen-frame shifting mechanism also operated by said key. 95

3. In a typewriting machine, the combination with a carriage, a platen and a platen frame mounted on the carriage to shift for writing capitals, of latches at the ends of the carriage to catch over the platen frame to hold it in one position, a rock-shaft extending along and mounted upon the carriage, 100 both of said latches being fixed to said rock-shaft, a roll swiveled on said rock-shaft about midway of the length of the latter, a shift-key operating a rail to engage said roll to rock the shaft and release the latches, 105 and a platen-frame shifting mechanism also operated by said key; said rail being constructed to detain said latches in released positions during the shifting movement of the platen frame. 110

4. In a typewriting machine, the combination with a carriage, a platen, and a platen frame mounted on the carriage to shift for writing capitals, of latches to operate between the ends of the carriage and the ends of the platen frame to hold the latter in one position, said latches being fixed to a rock-shaft, and a key-operated mechanism to shift the platen frame, a rail being operated by said key to engage a part projecting from said rock-shaft to rotate it to release the latches to permit the platen frame to be shifted by the key. 115 120 125

5. In a typewriting machine, the combination with a carriage, a platen, and a platen frame mounted on the carriage to shift for 130

writing capitals, of latches to operate between the ends of the carriage and the ends of the platen frame to hold the latter in one position, said latches being fixed to a rock-shaft, and a key-operated mechanism to shift the platen frame, a rail being operated by said key to engage a part projecting from said rock-shaft to rotate it to release the latches to permit the platen frame to be shifted by the key; said rail constructed to turn said projecting part out of its path, and having a face sufficiently broad to detain said projecting part during the shifting of the platen frame.

6. In a typewriting machine, the combination with a carriage, a platen, and a platen frame mounted on the carriage to shift for writing capitals, of latches to operate between the ends of the carriage and the ends of the platen frame to hold the latter in one position, said latches being fixed to a rock-shaft, and a key-operated mechanism to shift the platen frame, a rail being operated by said key to engage a part projecting from said rock-shaft to rotate it to release the latches, to permit the platen frame to be shifted by the key; and a spring tending constantly to return the latches to normal positions.

7. In a typewriting machine, the combination with a carriage, a platen, and a platen frame mounted on the carriage to shift for writing capitals, of latches at the ends of the carriage to catch over the platen frame to hold it in one position, a rock-shaft extending along and mounted upon the carriage, said latches being fixed to the rock-shaft, a key-operated rail to shift the platen, and an auxiliary rail secured upon said key-operated rail to engage a projection mounted upon said rock-shaft to turn the latter and release the latches.

8. In a typewriting machine, the combination with a carriage, a platen, and a platen frame mounted on the carriage to shift for writing capitals, of latches at the ends of the carriage to catch over the platen frame to hold it in one position, a rock-shaft extending along and mounted upon the carriage, said latches being fixed to the rock-shaft, a key-operated rail to shift the platen, and an auxiliary rail secured upon said key-operated rail to engage a projection mounted upon said rock-shaft to turn the latter and release the latches; said auxiliary rail having a face sufficiently broad to hold the latches released during the shifting of the platen frame, and means tending to return said latches to normal positions.

9. In a typewriting machine, the combination with a carriage, a platen, and a platen frame mounted on the carriage to shift for

writing capitals, of latches at the ends of the carriage to catch over the platen frame to hold it in one position, a rock-shaft extending along and mounted upon the carriage, said latches being fixed to the rock-shaft, a key-operated rail to shift the platen frame, and key-operated elements to release said latches, one element on the shift-rail and one on the rock-shaft, one of said elements in the form of a rail and constructed to turn the other element out of its path.

10. In a typewriting machine, the combination with a carriage, a platen, and a platen frame mounted on the carriage to shift for writing capitals, of latches at the ends of the carriage to catch over the platen frame to hold it in one position, a rock-shaft extending along and mounted upon the carriage, said latches being fixed to the rock-shaft, a key-operated rail to shift the platen frame, and key-operated elements to release said latches, one element on the shift-rail and one on the rock-shaft, one of said elements in the form of a rail and constructed to turn the other element out of its path; and having a face sufficiently broadened to detain said other element during the shifting of the platen frame.

11. In a typewriting machine, the combination with a carriage and a platen frame shiftable thereon and having a roll, of a rail mounted upon the machine frame to engage said roll to shift the platen frame, a latch device to hold the ends of the platen frame to the carriage, and two co-operative members, one mounted on the rail and the other mounted on the latch device, and constructed to release the latch device and hold it released during the shifting of the platen frame.

12. In a typewriting machine, the combination with a carriage, a platen and a platen frame mounted on the carriage to shift for writing capitals, of latches at the ends of the carriage to catch over the platen frame to hold it in one position, a rock-shaft extending along and mounted upon the carriage, said latches being fixed to the rock-shaft, a spring tending to rock said latches, a collar upon the rock-shaft, a roll swiveled on the collar, a shift-rail, the platen frame provided with a roll to be engaged by said shift-rail but normally disengaged therefrom, and an auxiliary rail fixed upon the shift-rail to engage and turn aside said roll, the auxiliary rail having a broad face to engage said roll to hold the latches released during the shifting of the platen frame.

JOHN C. McLAUGHLIN.
